UNITED STATES PATENT OFFICE.

ASHTON H. PRATT, OF CHICAGO, ILLINOIS.

TREAD-PIECE OR SOLE.

SPECIFICATION forming part of Letters Patent No. 740,311, dated September 29, 1903.
Application filed June 11, 1902. Serial No. 111,086. (No model.)

To all whom it may concern:

Be it known that I, ASHTON H. PRATT, of Chicago, in the county of Cook and State of Illinois, have invented certain new and useful Improvements in Tread-Pieces or Soles, of which the following is a specification.

This invention relates to the construction of the tread pieces or surfaces of boots and shoes, and has for its object to provide a structure which will be durable and economical and which will enable the utilization of small pieces of sole-leather while still providing a solid structure.

To these ends the invention consists in the constructions substantially as hereinafter described and claimed.

In the accompanying drawings, in which the invention is shown as embodied in a shoe-sole, Figure 1 represents an inverted plan view of a shoe-sole without a heel. Fig. 2 represents a section on line 2-2 of Fig. 1. Fig. 3 represents an edge view of the sole. Fig. 4 is a detail perspective view of another embodiment of my invention.

The same reference characters indicate the same parts in all the figures.

Referring first to Figs. 1, 2, and 3, a series of strips of leather are indicated at *a*, said strips extending from edge to edge of the sole and being cut from pieces of leather and secured together, so that their edges form the exposed bottom or tread-face of the sole. While said strips are shown as integral from end to end, it is to be understood that in some instances they may be made of two or more pieces placed end to end and so connected and secured, as hereinafter described, as to constitute practically continuous strips. In said Figs. 1, 2, and 3 a backing-piece *b* is shown, which backing-piece is preferably of leather, but may in some instances be of other suitable material. End pieces or clamping-blocks *e* are shown as secured to the backing-piece *b*, and the strips *a* are secured and clamped between said blocks, a wire or thread *f* being preferably employed, as hereinafter described.

A preferable way of manufacturing the sole is as follows: The strips *a* are first fastened together by being threaded or run upon the wire or thread *f*. Then one end piece *e* is secured to the back piece *b*, and the loop of wire

or thread at one end of the series of strips is passed between the two layers of which said end piece is preferably composed, the said wire being then drawn until it engages around the tacks or nails *g*, which secure the blocks *e* together and to the backing-piece *b*. The strips *a* are suitably glued or cemented together and, preferably under extremely heavy pressure, are pressed firmly up against the attached block *e*, and while the pressure is continued against said strips the other block *e* is applied to the backing-piece and the threads or wires are carried around the nails *g*, which secure the latter in place, the ends of the threads or wires being twisted or otherwise fastened.

As shown at *h*, nails may be driven through each individual strip *a* to additionally secure it to the backing-piece.

The toe and heel end pieces or clamping-blocks *e* are preferably made of two layers or lifts of leather, as indicated in the drawings. These toe and heel blocks not only afford means for holding the strips *a* in clamped position, but they also afford a more durable construction at the ends of the sole and are less liable to become displaced than would be the case if the strips *a* were continued to the ends of the sole, particularly the toe end. Said toe and heel blocks are of wide area relatively to the thickness of the strips *a*, and they are therefore not only well adapted to serve as abutments capable of permanently holding the strips clamped between them, as above described, but they may be trimmed off in the finishing operations on the shoe-sole without encroaching on the strips or causing any weakening of the wires on which the strips are strung. Moreover, said blocks are not liable to be deflected or spread away from the strips *a* in use, as would be the case if the extreme toe and heel portions were also strips similar to those which form the tread-surface under the ball of the foot. Owing to the fact that the toe and heel blocks are relatively wide, they are necessarily so placed relatively to the strips that the grain-surface is at a right angle to that of the strips. This is because, as above stated, the strips *a* are cut from pieces of leather and secured so that their edges form tread-surfaces of the sole. This construction of the end blocks provides

for holding the strips without liability of the end strips being separated from each other by wear, as would be the case if the end pieces were the same as the strips.

- 5 In some cases the nails *h* may be omitted and the wires *f* alone relied upon in addition to the cement or glue, such construction being indicated in Fig. 4. As shown in said figure, the backing-piece *b* may be omitted, particularly when a heel is to be made of the strips and blocks. This structure represented in Fig. 4 may be employed for the sole of sewed shoes, as the sewing-thread will engage each separate strip when the sole is fastened 10 to the shoe. For pegged or riveted shoes the strips should be previously attached to a middle sole, as the backing-piece *b* represented in Fig. 2.
- 15 Among the advantages of this invention the following may be mentioned: It provides a continuous wearing-surface of the full thickness of the sole, and said thickness may be limited only by the dimensions of the pieces which are cut out to form the strips *a*. The 20 thickness of the ordinary sole is limited by the thickness of the hide from which it is cut, whereas this structure provides for making a sole of any desired thickness according to the width of the strips *a* when first cut and 25 before they are placed face to face or back to back, so as to present their edges to form the bottom or tread-face of the sole. Furthermore, the sole can be produced economically,

as the strips *a* may be formed from scraps of hide, the principal portions of which are being otherwise used, and the sole is flexible and avoids creaking. 35

I claim—

1. A tread-piece for shoes having its wearing-surface composed of a plurality of strips 40 of leather secured together with their edges exposed to form the bottom or tread-face, and a relatively wide block against which the said strips are clamped, said block being of leather and having its grain-surface at a right angle 45 to that of the strips.

2. A sole comprising a relatively thin sole-shaped piece of material constituting a backing, leather toe and heel blocks at the ends of said backing, and a plurality of continuous 50 or unbroken strips of leather extending across the width of the sole and presenting their edges to the said backing and to the tread-face of the sole, the said backing, blocks and strips being secured together with the strips 55 clamped between said blocks, said blocks being relatively wide to permit trimming at the extreme toe and heel without impairing the fastenings, the grain-surface of the blocks being at a right angle to that of the strips. 60

In testimony whereof I have affixed my signature in presence of two witnesses.

ASHTON H. PRATT.
